LENS FOR HEAD LAMPS

Robert N. Falge, Anderson, Ind., assignor, by
mesne assignments, to General Motors Corpora-
tion, Detroit, Mich., a corporation of Delaware

Application December 7, 1932, Serial No. 646,067

2 Claims. (Cl. 240—41.4)

This invention has to do with lenses especially such as were employed in headlamps of the design described and claimed in the application of Charles E. Godey and Robert N. Falge, Serial No. 539,518, filed May 23, 1931.

In that application there are disclosed several headlighting systems in which each lamp supplies the light at the top of the beam on one side only, the combined beams from the two lamps producing a high beam having a substantially horizontal cutoff at the top. By depressing the beam from one lamp a passing beam is obtained which is higher on one side than on the other. In this type of design it is essential that the lamp providing the light at the top of the beam on the right hand side of the road should have a fairly sharp cutoff on its left edge with the maximum intensity as near the left edge as possible so that when the passing beam is used the high intensity will reach as far down the road as possible without causing glare to an approaching driver on a straight road. In that application there are set forth several principles of design which produce the desired lateral cutoff. This invention has to do with a further improvement in design having the same object. The result is achieved by employing flutes having faces of S-shape with a portion of the face between the edges nearest parallel with the opposite side of the lens so that the rays forming the left edge of the beam pass through said portion while the rest of the light is directed in varying degrees to the right. This design is desirable because in production it is possible to form the central portion of the flute more accurately than the edge portions. The edge portions are deformed by fillets on the glass, sagging of the glass in molding, etc., and consequently the light passing through them is erratically directed.

40. In Figure 1 I have shown a front view of a lens embodying this invention.

Figure 2 is a section on line 2—2 of Figure 1.

Figure 3 is a similar section on an enlarged scale showing a few of the improved flutes and the direction of rays passing through them.

45. Figure 4 shows the application of my improved flute to a concavo-convex lens.

In Figure 1 I have shown a lens such as is used on automobile headlamps provided with wide flutes 10 over the central portion, and narrower flutes 12 over the top and bottom portions. The specific arrangement of flutes forms no part of the present invention.

50. In Figures 2 and 3 I have shown in detail the design of the flutes 10. It will be noted that each

flute has an S-shaped outer face with a portion 11 of the face between the edges of the flute approximately parallel to the opposite face of the lens. This is further indicated in Figure 3 where ray 14 is shown passing through the portion 11 of the flute without being altered in direction, while rays 16 and 18, passing through the edges of the flute, are directed sharply toward the right. Intermediate rays will be bent in amounts varying between these limits. With this design rays 14 will therefore form the left boundary of the pattern. The advantage of this arrangement is that the portion 11 can be accurately formed in the molding operation, thereby insuring the accurate location of the left boundary of the beam and the concentration of light near the left boundary. The portions of the lens next to the risers 17 are subject to malformation in the pressing operation. Such malformation may come from fillets formed at the corners of the glass or from sagging of the glass in molding. I have used the term "fillet" in the sense in which it is used in this art to mean the rounded corners obtained both at the top and bottom of the risers 17 between flutes. The fillets have been shown on the drawing somewhat exaggerated in size. Whatever be the design of flutes the effect of the fillets is to scatter light over a wide angle so that such light does not form a part of a useful beam. The amount of light scattered by the fillets is so little that the intensity is not seriously objectionable from the glare standpoint. The radius of the fillets varies substantially in production, depending upon the temperature of the mold, glass, etc. As the radius becomes larger the fillet intercepts the useful portion of the flute farther toward the center. The maintenance of the direction of the last ray from the useful flute area therefore depends upon the maintenance of the correct radius of the fillet. This limitation is avoided with my improved form of flute as shown in Figures 2 and 3, since the light from the portions of the flute nearest the risers is thrown far to the right and no attempt is made to secure an accurate boundary at this side of the beam. Where, however, a conventional flute is used the radius of the fillet determines the portion of the lens through which the rays will pass that form the left boundary of the beam. Variation in radius of the fillets cannot be avoided in production so that it becomes difficult, if not impossible, to accurately locate the left boundary of the beam with the old style flute.

Another difficulty in directing the maximum in-

tensity as far to the left as possible arises from the fact that certain portions of the flute sag when the glass cools in the mold. This sag changes the direction of light through portions 5 of the flute affected. It is desirable that this sagging effect be concentrated in portions of the flute which direct light well to the right. In the case of the conventional flute experience has shown that the sag occurs in the portion of the 10 flute which provides light near the left boundary of the beam. With the new flute the difficulty from sagging is largely avoided because the tendency to sag is restricted to portions of the flute next to the risers.

15 I have shown in Figure 4 that these flutes may be employed with concavo-convex lenses such as are now commonly used on automobiles. Here a portion 22 of the flute is substantially parallel with the opposite face of the lens, while the edge 20 portions diverge increasingly therefrom.

I claim:

1. A molded glass lens provided over the portion thereof which is adapted to transmit light rays to define a side edge portion of the beam with a plurality of substantially vertical flutes 80 each having a face in the shape of an S-curve with an intermediate portion of the face nearest to parallel with the opposed face of the lens so that the rays passing therethrough are deflected the least and define said side edge portion, the 85 portions of the flute on either side of the said intermediate portion directing light to the same side of the said edge portion whereby a sharp cut-off is obtained at the same edge.

2. In the lens as defined in claim 1 said flute 90 faces being connected by risers extending substantially in the direction of the projected rays.
